US00D853874S

(12) **United States Design Patent** (10) **Patent No.:** **US D853,874 S**
Pare et al. (45) **Date of Patent:** **** Jul. 16, 2019**

(54) **SMOKE DETECTOR**

(71) Applicant: **Apollo Fire Detectors Limited**, Hampshire (GB)

(72) Inventors: **Graham Ian Pare**, Hampshire (GB); **Philip Alan Coulter**, Hampshire (GB); **Philip Watson**, Hampshire (GB)

(73) Assignee: **APOLLO FIRE DETECTORS LIMITED**, Hampshire (GB)

(**) Term: **15 Years**

(21) Appl. No.: **29/571,394**

(22) Filed: **Jul. 18, 2016**

(30) **Foreign Application Priority Data**

Jan. 28, 2016 (EM) 002962399-0001

(57) **CLAIM**

The ornamental design for a smoke detector, as shown and described.

DESCRIPTION

FIG. 1 is a bottom, front, left side isometric view of a smoke detector;

FIG. 2 is a top plan view thereof;

FIG. 3 is a bottom plan view thereof;

FIG. 4 is a front view thereof;

FIG. 5 is a right side view thereof;

FIG. 6 is a left side view thereof; and,

FIG. 7 is a rear view thereof.

The broken lines illustrate portions of the smoke detector that form no part of the claimed design.

1 Claim, 3 Drawing Sheets
